UNITED STATES PATENT OFFICE.

ARTHUR HARDONCOURT, JR., OF BROOKLYN, NEW YORK.

WALL CONSTRUCTION AND CHANNEL BRICK OR BLOCK THEREFOR.

1,311,069.

Specification of Letters Patent. Patented July 22, 1919.

Substitute for application Serial No. 695,379, filed May 6, 1912, which was renewed on February 23, 1915, Serial No. 10,129. This application filed July 16, 1915. Serial No. 40,250.

To all whom it may concern:

Be it known that I, ARTHUR HARDONCOURT, Jr., a subject of the Emperor of Austria, and a resident of Brooklyn, New York, 5 in the county of Kings and State of New York, have invented an Improvement in Wall Construction and Channel Bricks or Blocks Therefor, of which the following description, in connection with the accompanying drawings, is a specification, like letters on the drawings representing like parts.

The present invention relates to hollow wall construction and a channel brick therefor, the present application constituting a 15 substitute for my application filed May 6, 1912, Serial No. 695,379, which was renewed on February 23, 1915, as Serial No. 10,129.

The object of the present invention is to provide an improved channel brick and a 20 hollow wall construction embodying such channel brick, which wall construction shall be practically moistureproof and effectively prevent the penetration of moisture from the outer to the inner face thereof, and one in 25 which the longitudinally extending mortar-joints are separated by longitudinally extending air spaces.

A further object of the invention is to produce a moistureproof wall embodying my 30 improved channel brick combined with a facing of standard brick, and to produce a channel brick which in construction and size, shall be adapted for use with standard brick so that a standard brick bond may be projected into and received by the channel brick portion of the wall at any given line of channel brick construction, thus providing for 35 the effective bonding of the standard brick facing to the channel brick portion of the wall, and whereby ordinary brick may be effectively used at any point in the channel brick portion of the wall for the purpose of closing the open-ended channels and finishing the wall at angles and corners and 45 around window and door openings.

Further objects of the invention will be set forth in connection with the following description of my improved channel brick and hollow wall construction.

50 The invention is illustrated in the accompanying drawing in which—

Figure 1 illustrates a transverse section through a hollow wall construction embody-

ing my invention, in which the wall comprises a section constructed of channel brick 55 with a facing of standard brick laid against and bonded thereto.

Fig. 2 illustrates a perspective view of the improved channel brick, such as is illustrated in Fig. 1.

Fig. 3 illustrates a transverse section through a hollow wall construction omitting the facing of standard brick and embodying a slightly modified form of channel brick.

Fig. 4 illustrates a perspective view of the 65 channel brick employed in the wall construction shown in Fig. 3.

Similar reference characters will be employed throughout the specification and drawing to designate corresponding parts.

In the drawing, 1 represents a suitable 70 foundation upon which the hollow wall construction 2 is built up.

As shown in Fig. 1, the hollow wall construction 2 comprises superimposed longitudinally extending rows of my improved channel brick 3. The channel brick 3 as shown in Fig. 2, is constructed of clay which is dried and kiln-burned in the usual manner of manufacturing brick, and it comprises a 80 body portion 4, from one surface of which project webs 5, and when the channel brick is made double as shown in Fig. 2, the body portion 4 will correspond in size and dimensions to two standard brick laid parallel 85 and side by side; that is to say, assuming that a standard brick is 4x8, which is the usual size of well known standard brick, the size of the body portion 4 of my channel brick will be 8x8.

When made double standard brick size, my 90 channel brick as shown in Fig. 2, will be provided with a web 5 extending along each of the outer edges of the body portion 4 and a web 5 located at an intermediate 95 point.

Upon the upper surface of the body portion 4 the channel brick 3 will be provided with upwardly projecting ribs 6 which extend parallel to each other and are of a 100 width considerably less than the space between the depending webs 5 and are positioned directly over the space between the webs 5, thus producing along the outer edges of the ribs 6 the angular recesses or seats 7 105 with the intermediate recess or seat 8.

Between the webs 5 there are provided open spaces 9 extending parallel to each other from end to end of the channel brick and preferably extending in the form of a 5 groove 10 beneath the ribs 6 longitudinally thereof, whereby the wall of the channel brick is substantially of uniform thickness throughout, and thus a tendency to warp, in manufacture, is counteracted to a great extent. 10

As heretofore indicated, the double form of channel brick is practically twice the size of two standard brick, and the outer faces 11 are substantially the size and shape of the 15 face of a standard brick; that is to say, assuming that the standard brick is 8 inches by 4 inches in the largest area, and 8 inches by 2 inches in its smaller area or its "face" area, the sides 11 will be 8 inches by 2 inches. 20

The wall 2, as before stated, is built up of a plurality of superimposed rows of the channel brick 3 laid so that the spaces 9 between the webs 5 will run longitudinally of the wall and in the construction of the wall 25 the webs 5 will be seated in the independent mortar joints 12 formed by the mortar in the recesses 7 and 8, the ribs 6 of one channel brick being received within the spaces 9 of a superimposed channel brick. 30

By this construction, it will be noted that the hollow wall construction comprises longitudinally extending channel brick inclosing longitudinally extending air spaces and separate and independent longitudinally 35 extending mortar joints, and that as the mortar joints are separate and independent, no moisture can penetrate from one surface to the other surface of the wall. It will be further noted that the air spaces also act as 40 a preventive of the penetration of moisture through the wall.

The upwardly extending ribs are made somewhat narrower than the space between the webs, so that while they form a guide 45 for accurately positioning one channel brick on another, the ribs nevertheless, are substantial in size and have not the tendency to warp during the baking process or to become distorted, thus insuring at all times the 50 ready insertion of the ribs in the space or opening between the webs.

The wall as shown in Fig. 1, comprises a facing of standard brick 13, which are laid up in the usual manner and held in position 55 by means of mortar joints 14, and as the standard brick and the channel brick are of the same height and length, when the standard brick are laid as shown in Fig. 1, each layer thereof will be in the same plane as 60 any particular row of channel brick, so that when it is desired to secure the facing of standard brick and the hollow wall together, as by means of a bonding row 15 of standard brick, this may be accomplished by dividing 65 the channel brick in this row or by using a

channel brick having a single channel and inserting the standard brick so that a portion of the standard brick extends into the hollow wall construction and a portion of it extends into the facing of standard brick, as 70 shown at 15. In making this bonded connection, one of the upstanding ribs 6 of the channel brick in the course below will be partially broken off or removed as shown at 16. 75

It will be noted that I have produced a channel brick which lends itself readily because of its size with relation to a standard brick, to being combined with such standard brick in the building up of a wall. 80

The lower edges of the webs 5 may be enlarged or given an extended bearing area by means of the projections 17, although such feature is not essential and may be dispensed with. 85

Such a wall as I have shown and described in Fig. 1, may receive upon its inner surface plaster or other finish directly applied thereto, without the necessity of using any other means for receiving and supporting the plaster, and in order to effectively anchor the plaster surface to the wall, the channel brick 3 may be provided along the outer exposed faces thereof with the dovetail grooves 18 which receive a portion of the plaster finish 95 and will effectively hold such finish to the wall surface. 90

In Fig. 3 the hollow wall is built up of channel brick exactly like the channel brick which has been described and consists of 100 parallel rows of such channel brick, the webs 5 of which are secured by mortar joints 12 and which has the longitudinally extending air spaces 9, the only difference between this wall and the one shown in Fig. 1 being, that 105 it is not provided with a standard brick facing, and in this form of wall the channel brick such as shown in Fig. 4 is employed, in which the sides 11 are formed without the longitudinally extending dovetail groove 110 and one side of which is provided with any suitable finish, such as the roughened finish as shown at 11, commonly called wirecut finish, corresponding in all respects to the finish of a wirecut standard brick, whereby, when 115 built up into a wall construction, the outer face of the wall will have the appearance of being constructed of standard brick with a wirecut finish.

My improved channel brick is, as before 120 stated, made of any brickmaking material, and while combining all the advantages of lightness and strength of a standard brick, has the additional advantage of being twice the size of a standard brick, while relatively 125 light in weight, thus permitting the laying of what is the equivalent of two standard brick at a single operation. A further advantage is the adaptability of the channel brick to be combined with standard brick 130

because of its size with relation to the size of a standard brick. A further advantage is, that while it has all the appearance of a standard brick when built up into the wall, 5 a practically moistureproof wall is produced by the longitudinally extending air spaces, without materially weakening the strength of the brick. A further advantage resides in the facility with which the channel brick 10 may be positioned, one row with relation to a subjacent row, the positioning of the webs being guided by the ribs and mortar seats as hereinbefore set forth.

I would point out that in so far as I am 15 aware of the prior state of the art, I am the first to produce a channel brick provided with a longitudinally extending air space between parallel webs, the outer faces of the webs or the side faces of the channel brick 20 corresponding in size to the face of standard brick, whereby my channel brick is adapted to be combined, and to readily adapt itself for use with standard brick, and this feature I regard as one of the most important features of my invention.

Of course, it is to be understood that instead of making my channel brick double, as shown in Figs. 2 and 4, it can be made single, that is to say, exactly one-half the 30 width, or exactly the size of one of the larger surfaces of the standard brick, in which event the channel brick would have only two depending webs 5 and only one upstanding rib 6. Otherwise, the construction 35 will be the same as that illustrated and described. Such a brick is shown in the second course from the top of Fig. 1.

My improved channel brick is to be clearly distinguished from cement blocks such as 40 shown in the patent to Shaw, #676,803, of June 18, 1901, as unlike such blocks my channel brick are made of clay and by the use of any usual brick making machines and after being formed are baked in the usual 45 manner of making brick, and in order to prevent the warping of the brick while being baked all parts thereof are preferably of uniform thickness. Most important, however, is that my channel brick are of such a 50 size as to be readily combined with standard brick in the formation of a wall.

Having described my invention, I claim:

1. Hollow wall construction, comprising horizontal rows of superimposed longitudinally extending channel brick, each channel brick comprising a body portion and parallel webs projecting from the body portion at right angles thereto and spaced apart from each other forming an open channel, 55 the space between the projecting webs being open from end to end and the webs and body portion being co-extensive in length, and the outer faces of such webs being rectangular and approximately corresponding in size to 60 the face of a standard brick, the whole being

of substantially uniform thickness throughout; the channel brick in one row combining with the body portions of the channel brick of a subjacent row to form longitudinally extending superimposed air spaces; 70 and longitudinally extending parallel mortar joints uniting said rows of channel brick, the mortar joints being adjacent the opposite faces of the wall and separated by the air space. 75

2. Hollow wall construction, comprising horizontal rows of superimposed longitudinally extending channel brick, each channel brick comprising a body portion and parallel webs projecting from the body portion 80 at right angles thereto and spaced apart from each other and forming an open channel, the space between the projecting webs being open from end to end and the webs and body portion being co-extensive in length, 85 the outer faces of such webs being rectangular and approximately corresponding in size to the face of standard brick, such rows of channel brick being secured to each other by longitudinally extending separate and 90 independent mortar joints, and a facing of standard brick laid against one face of the hollow wall comprising rows of standard brick superimposed and extending in longitudinal rows corresponding to the rows of 95 channel brick.

3. Hollow wall construction, comprising horizontal rows of superimposed longitudinally extending channel brick, each channel brick comprising a body portion and parallel webs projecting from the body portion at right angles thereto and spaced apart from each other and forming an open channel, the space between the projecting webs being open from end to end and the webs and body portion being co-extensive in length, 100 the outer faces of such webs being rectangular and approximately corresponding in size to the face of standard brick, such rows of channel brick being secured to each other by longitudinally extending separate and independent mortar joints separated by an air space, and a facing of standard brick laid against one face of the hollow wall and comprising standard brick 105 superimposed and extending in longitudinal rows corresponding to the rows of channel brick and bonded to the hollow wall at intervals by a row of standard brick 110 transversely arranged and extending partially into the hollow wall and the standard brick facing. 115

4. A channel brick, comprising a body portion, parallel webs projecting therefrom at right angles thereto and spaced apart 120 from each other, the space between the projecting webs being open from end to end and the webs being co-extensive in length with the body portion, said webs being rectangular and approximately corresponding 125 to the face of a standard brick, the whole being 130

4
in size to the face of a standard brick, and
said body portion having a rib upon the sur-
face thereof opposite the webs and disposed
longitudinally above the space between the
5 webs and narrower than the space between
the outer edges of the webs, and a longi-
tudinal groove beneath the rib.

In testimony whereof, I have signed my
name to this specification, in the presence of
two subscribing witnesses.
